[57] CLAIM

The ornamental design for a pedestal mounted marine power source, as shown and described.

DESCRIPTION

FIG. 1 is a front elevational view of a pedestal mounted marine power source showing my new design;

FIG. 2 is a rear elevational view thereof;

FIG. 3 is a right side elevational view thereof, the left side being a mirror image of that shown;

FIG. 4 is a top plan view thereof;

FIG. 5 is a bottom plan view thereof; and

FIG. 6 is a top, front and left side perspective view thereof.
